UNITED STATES PATENT OFFICE.

JOHN BEDFORD FARRELL, OF GREENSBOROUGH, NORTH CAROLINA.

DESIGN FOR A STANDARD FOR FRUIT-CUTTERS.

SPECIFICATION forming part of Design No. 38,135, dated August 28, 1900.

Application filed November 18, 1899. Serial No. 737,531. Term of patent 14 years.

To all whom it may concern:

Be it known that I, JOHN BEDFORD FARRELL, a citizen of the United States, residing at Greens-
borough, in the county of Guilford and State
5 of North Carolina, have invented and pro-
duced a new and useful Design for a Stand-
ard for Fruit-Cutters, of which the following
is a specification, reference being had to the
accompanying drawing, in which is shown a
10 perspective view of a fruit-cutter standard
embodying my new design.

The leading features of my design consist
of an upright portion having a flaring base

at its lower end and a curved enlargement or
head at its upper end, having flattened sides 15
and formed with a slot substantially midway
and parallel with the flattened sides.

Having thus fully described my invention,
what I claim as new, and desire to secure by
Letters Patent, is—

15 The design for a fruit-cutter standard, as
herein shown and described.

JOHN BEDFORD FARRELL.
